United States Patent Office

Des. 185,244
Patented May 19, 1959

185,244

PLATE OR SIMILAR ARTICLE

Gerald S. Stone, Scarsdale, N.Y., assignor to Johnson Bros. (Hanley) Limited, Hanley, Stoke-on-Trent, England, a British company

Application December 29, 1958, Serial No. 53,930

Term of patent 14 years

(Cl. D44—15)

The figure is a top plan view of a plate or similar article of conventional configuration showing my new design.

I claim:

The ornamental design for a plate or similar article, substantially as shown and described.

References Cited in the file of this patent

UNITED STATES PATENTS

D. 65,462 Beebee ----- Aug. 26, 1924
D. 125,304 DeKort ----- Feb. 18, 1941

OTHER REFERENCES

A Chronology of Spode Patterns, pamphlet, rec'd April 29, 1935, p. 1, top plate.
Crockery and Glass Journal, January 1957, p. 60, The Old Mill, left center of page.